MILES DAWSON, OF NEW HAVEN, CONNECTICUT

SANITARY GARBAGE-CAN ATTACHMENT.

1,360,732.

Specification of Letters Patent. Patented Nov. 30, 1920.

Application filed February 28, 1920. Serial No. 361,972.

To all whom it may concern:

Be it known that I, MILES DAWSON, a subject of George V of Great Britain, residing at New Haven, in the county of New Haven, 5 State of Connecticut, have invented certain new and useful Improvements in Sanitary Garbage-Can Attachments; and I do hereby declare the following to be a full, clear, and exact description of the invention, such as 10 will enable others skilled in the art to which it appertains to make and use the same.

This invention relates to conveyer chutes, and more especially to those intended for garbage and having pivoted gates; and the 15 object of the same is to produce an attachment which may be applied to the cover of a receptacle such as a can and by means of which garbage can be introduced therewith into the least escape of odors.

20 A further object is to provide for the introduction of garbage in charges, as for instance in paper containers to be dropped bodily into the can.

25 A further object is to provide for the admission of fresh air to the attachment so as to ventilate the same.

It is to be understood that, while the 30 invention is shown in the form of a comparatively short hopper applied directly to and supported by the top of an ordinary garbage can, it may be a chute of considerable length so that the user can introduce the charges of garbage at a high point, and they will be received in a receptacle located 35 some distance below, the latter possibly serving as the joint receiving receptacle for a number of such chutes.

One application of the idea is set forth 40 in the following specification and shown in the drawings wherein:

Figure 1 is a vertical section through the can and its top and the lower portion of this attachment, showing the gate in full lines as closed and in dotted lines as open.

45 Fig. 2 is a sectional view showing the gate as open and illustrating the passage of a container through it.

In the present case the receptacle is shown 50 as a garbage can G having a top T, and the container C may be a box made of paper or the like in which the user accumulates garbage until it is full, and then drops the container and its charge bodily into the hopper 55 or chute, whence it falls into the can G. In the ordinary use of the garbage can, the refuse from the house is carried in a portable receptacle to the can, the top is lifted off, the garbage is scraped out of the receptacle into the can, and then the top is 60 put back. Thus there has been a considerable interval when the odors from the garbage in the can, some of which may have been there for a considerable time, are permitted to escape. In apartments and other places where long chutes lead to a receptacle, the odors escape from the upper ends 65 of the chutes when they are opened to put in the refuse, and the latter on its way down fouls the walls of the chutes so that they in turn give off odors until they are cleaned. It is proposed by the present invention to handle the charge of garbage in a container so that the walls of the chute or hopper 70 may be kept clean, and also it is proposed that a gate shall stand constantly closed across the chute or hopper just above the receptacle so as to prevent the escape of odors, this gate being latched closed by the 75 raising of the cover, released when the cover is closed, and itself opened by the weight of the container with its charge. Therefore the chute or hopper is doubly closed to the 80 escape of gases and odors, and its walls are 85 protected from contamination.

Referring now to the embodiment of the 90 invention set forth herewith, the top T of the receptacle is cut to form a hole preferably rectangular and to it around said hole is secured a frame 1 having an upstanding flange 2 which preferably flares slightly as shown. Into this flange is seated the lower end of a hopper 3, secured by screws, pins or other fastening devices 4. Certain or all 95 of the walls may flare externally but be upright internally so that they grow thicker toward their edges as seen in Fig. 2, and into such wall from its outer side is bored or formed a cavity 5, from which a fine vent opening 6 leads upward. The upper edge 100 of the hopper is rabbeted as seen at 7 so as to produce a flange or rib 8 around its periphery and outside of all the vents 6. A cover 9 is provided for the hopper, hinged or otherwise fastened thereto as at 9', and adapted when closed to rest on the peripheral rib so that the vents are not closed even though the cover may be. The result is that 105 fresh air is permitted to enter the cavities 110 and flow upward to ventilate the hopper.

A door or gate 10 is mounted within and

adapted to close upward into the frame, this gate being pivoted at 11 and having an arm 12 projecting rearward beyond its pivot and carrying a counterweight 13 sufficiently large to hold the gate normally closed. One end of the pivot rod carries a catch 14, and pivoted at 15 to one side of the hopper is a latch 16 whose heavier front arm is adapted to fall normally into engagement with said catch when the gate is closed, and hold it in that position. Above the rear arm of the latch in guides 17 is mounted an upright pin 18 of sufficient length to be depressed by the cover 9 when the latter is closed, and by this means the closing of the cover automatically trips the latch. Of course it would be possible to provide some other form of counter balance, as for instance a spring which would hold the gate normally closed, but the attachment as herein shown and described is purposely designed so that it can be made mostly of metal and wood at little expense, and easily assembled and kept clean; in fact, it would not require the services of a skilled mechanic to apply this attachment to the top of the ordinary garbage can of commerce, although probably can-tops so equipped will be manufactured and sold to the consumer.

In use, it is preferred as suggested that the garbage be accumulated in the container C, or at least put into the can in a charge held in bulk by some kind of a wrapper, and if the wrapper or container be of paper it will soon be dissolved. The user raises the cover 9, and the parts stand as seen in full lines in Fig. 1, whether the hopper is short as there shown or is of considerable height and perhaps extended to such length that it becomes in effect a chute. The weight of the latch causes it to drop so that it engages the catch and the gate is locked closed. The charge of garbage in its container C is now put into and dropped through the hopper, and it falls on and is supported by the gate. The user next closes the cover, thereby depressing the pin and raising the latch 16, the weight of the charge overbalances the counter weight and tips the gate, and the charge slides downward as seen in Fig. 2. As soon as it has passed, the counterbalance 13 closes the gate and holds it so, although the closed cover now holds the latch 16 raised. Thus odors from the receptacle could not escape when the cover was first raised because the gate was then closed, could not escape when the gate was open because the cover was then closed, and cannot now escape because both are closed; and even the interior of the hopper is ventilated at all times. The widest latitude as to details is reserved, and the word "hopper" as employed in the following claims should not be restricted unduly.

What is claimed as new is:

1. In a conveyer of the type described, the

combination with a hopper leading to a receptacle; of a cover at its upper end normally closed by gravity, a pivoted gate at its lower end closing upward, means holding the gate normally closed but adapted to yield under the weight of a charge, means for latching the gate positively closed, and means for tripping the latch by the closure of the cover.

2. In a conveyer of the type described, the combination with a hopper leading to a receptacle; of a cover at its upper end normally closed by gravity, a pivoted gate at its lower end closing upward, means holding the gate normally closed but adapted to yield under the weight of a charge, a catch on said gate, a latch on the hopper adapted to automatically engage said catch, and means for holding said latch tripped while the cover is closed.

3. In a conveyer of the type described, the combination with a hopper leading to a receptacle; of a cover at its upper end normally closed by gravity, a pivoted gate at its lower end closing upward, means holding the gate normally closed but adapted to yield under the weight of a charge, a catch on said gate, a latch pivoted to the hopper and having its heavier end normally standing in the path of said catch, and an upright push rod mounted in guides on the hopper above the lighter end of the latch and adapted to be depressed by the closing of the cover.

4. The combination with a receptacle whose top has an opening, a frame around said opening, a hopper mounted in the frame, and a hinged cover for closing the top of the hopper; of a gate pivoted in the frame and closing upward against the bottom of the hopper, overbalancing means for holding the gate normally closed, a catch fast on the pivot of the gate, a latch movably mounted on the hopper and normally engaging said catch, and trip mechanism on the hopper for raising the latch by the closing of its cover.

5. The combination with a receptacle whose top has an opening, a frame around said opening, a hopper mounted in the frame, and a hinged cover for closing the top of the hopper; of a gate pivoted in the frame and closing upward against the bottom of the hopper, an arm projecting to the rear from its pivot, a weight thereon adapted to hold the gate normally closed but to yield for the passage of a charge, a catch fast on the pivot of the gate, and latching mechanism on the hopper normally in position to engage the catch and hold the gate closed but thrown out of such position by the closing of the hopper-cover.

6. The combination with a garbage can whose top has an opening, and a hopper mounted on the top around said opening,

its walls having cavities in their outer sides and vents leading thence upward and opening through their upper edges, and the latter having a rib inclosing all the vents; of a 5 cover hinged to the top of the hopper and adapted to close onto said rib without closing the vents.

7. The combination with a garbage receptacle, a hopper opening into its top, and a 10 manually operable cover at the top of the hopper; of a gate pivoted within the hopper, yielding means closing it normally upward,

means locking it closed by the closure of the cover but released when the cover is opened, and containers for garbage of a size to be 15 dropped through the hopper and with their contents having weight sufficient to overcome said yielding means, as described.

In testimony whereof, I affix my signature, in the presence of two witnesses.

MILES DAWSON.
